UNITED STATES PATENT OFFICE.

THOMAS CLEMENT MERRIMAN, OF TUNSTALL, ENGLAND, ASSIGNOR TO WILLIAM S. PITCAIRN CORPORATION, OF NEW YORK, N. Y., A CORPORATION OF NEW YORK.

DESIGN FOR A COVERED DISH.

Application filed September 22, 1925. Serial No. 14,846. Term of patent 3½ years.

To all whom it may concern:

Be it known that I, THOMAS CLEMENT MERRIMAN, a subject of the King of Great Britain and Ireland, residing at Tunstall, county of Stafford, England, have invented a new, original, and ornamental Design for a Covered Dish, of which the following is a specification, reference being had to the accompanying drawing, forming part thereof.

I claim:

The ornamental design for a covered dish as shown.

THOMAS CLEMENT MERRIMAN.
